CLAIM

The ornamental design for a display rack, as shown and described.

DESCRIPTION

FIG. 1 is a perspective view of a display rack showing my new design, the two sides not shown being identical in appearance to the sides shown;

FIG. 2 is a side elevational view of a second embodiment of the display rack shown in FIG. 1, the sides not shown being identical in appearance to the side shown;

FIG. 3 is an enlarged fragmentary side elevational view taken along line 3—3 of FIG. 2;

FIG. 4 is an enlarged bottom plan view; and

FIG. 5 is an enlarged fragmentary top perspective view thereof.
